(57) **CLAIM**

The ornamental design for a circuit board for an electrical connector, as shown and described.

DESCRIPTION

FIG. 1 is a front perspective view of a circuit board for an electrical connector showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear, bottom perspective view thereof.

The broken lines shown in the drawings are only provided to illustrate the environment of the design, and form no part of the claimed design. The surface area that lies between the top and bottom panels of the circuit board for electrical connector forms no part of the claimed design.
